(57) **CLAIM**

The ornamental design for a gaming machine belly panel as shown and described.

DESCRIPTION

FIG. 1 is a perspective view from above and to the right of a gaming machine belly panel showing the design.

FIG. 2 is a perspective view from below and to the left of the gaming machine belly panel shown in FIG. 1.

FIG. 3 is a front view of the gaming machine belly panel shown in FIG. 1; and,

FIG. 4 is a bottom view of the gaming machine belly panel shown in FIG. 1.

The dashed broken lines in the drawings show environment for the gaming machine belly panel and form no part of the claimed design. The dot-dashed broken line in the drawings depicts a portion of the gaming machine belly panel that forms no part of the claimed design.

1 Claim, 4 Drawing Sheets
